UNITED STATES PATENT OFFICE.

CORNELIUS AMBRUSTER AND HAROLD MCK. BECK, OF CHICAGO, ILLINOIS.

DAMPER-REGULATOR.

954,493.

Specification of Letters Patent. Patented Apr. 12, 1910.

Application filed January 12, 1906. Serial No. 295,676.

To all whom it may concern:

Be it known that we, CORNELIUS AMBRUSTER and HAROLD MCK. BECK, residents of the city of Chicago, county of Cook, and 5 State of Illinois, have invented certain new and useful Improvements in Damper-Regulators; and we do hereby declare that the following is a full and true description thereof, reference being had to the accompanying 10 drawings.

Our invention relates to that class of devices which have for their purpose the regulation of furnace drafts by the automatic opening and closing of the pipe and door 15 dampers, and has special reference to that class of devices wherein electricity is used to actuate the device.

In the drawings, Figure 1 is a perspective of our regulator, Fig. 2 is a rear view and 20 Fig. 3 is a sectional end view of the same. Fig. 4 is a diagram of the electrical connections of our device; Fig. 5 is a detail of a modification of our crank and Fig. 6 is a detail of our device.

25 More particularly described, A represents the chest in which our motor mechanism is inclosed, and consists of a metallic chamber designed to be attached to a wall or ceiling.

B represents the double crank which carries 30 the connections with the pipe and door dampers. This crank B has a journal bearing in said chest A and is in two parts held together by a clamping screw b which permits of the adjustment of said crank B. 35 The crank B carries two opposed crank ends b¹ and b², which by means of chains x and x¹, are connected with the pipe and door dampers respectively. Upon the shaft of the crank B, near the face of the chest A, 40 is placed a sprocket C, which is fitted with interior cam shoulders c c. Through a suitable perforation in the diameter of the crank B in opposition to cams c c, a pin b³ rides loosely and engages with the cams c c. Upon 45 this sprocket C is placed a chain c¹ which has attached to its end a weight c².

In operation, when the weight c² shall have reached the lower end of the pin c¹, the weight may again be drawn up to the 50 crank B by the reverse action of the sprocket C, and without the rotation of the crank B; the sprocket C moving independently of the crank B. On the opposite end of the crank B, or the end which projects within the chest 55 A, there is fixed a cross arm b⁴. Upon either end of this cross arm b⁴, are fixed studs b⁵,

which project forward toward the front face of chest A, but do not have contact with the same. Also upon the forward face of the cross arm b⁴, is fixed a tongue spring b⁶, 60 which is designed to effect the electrical connection hereinafter described. Attached to one end of the cross arm b⁴, and also to the wall of the chest A, is an air check P which has for its purpose the control of the cross 65 arm b⁴. Upon the inner face of the chest A is attached an electro-magnet D. In opposition thereto is fixed an armature d which has rocking connection with said chest A at the point d¹; a stop d² is also rockingly connected with the chest A at the same point d¹. The end of the stop d², nearest the cross arm b⁴, being further removed from the rocking point d¹ than the opposite end thereof, the 70 said end nearest the said cross arm lies normally downward. To prevent its dropping beyond the point desired, a small block d³ is attached to the face of the chest A and acts as a stop to check the said downward movement. Armature d is fitted at its forward 75 end with a small stud which engages a perforation in the stop d² and enables the armature d to act as a hammer to lift the stop d² at the desired time. The stop d² is so placed that normally it lies in contact with 80 one of the studs b⁵. This stop, d² is added in the device for releasing the cross arm b⁴ in order that the release may be effected by a hammer blow of the said armature d upon 85 said stop d². This affords the opportunity 90 of using very much less voltage than would be necessary were the armature d engaged directly with the cross arm b⁴ and allows us to use a more economical amount of electrical power. Devices of this character have 95 been erected heretofore wherein the armature had direct engagement with the cross arm b⁴ and in practice it is discovered that too much electrical power is needed to effect the release to make the device commercially 100 possible. Our hammer blow device overcomes this objection.

In operation when an electric circuit is completed and the current sent through the electro-magnet D, the armature d is drawn 105 into contact with the said electro-magnet and acting upon the stop d², it lifts it out of contact with the stud b⁵. The cross arm b⁴ is then released and the crank B subject to the action of the weight c², the weight 110 then drops and the crank revolves thereby opening or closing the draft as the case may

be; the revolution of the crank and the cross arm b^4 being controlled by the air check P. When the cross arm b^4 starts the revolution, the electric circuit is broken and the stop d^2 drops back into its engaging position. Therefore, when the cross arm b^4 has completed a semi-revolution, the opposite stud b^5 comes into contact with the stop d^2 and the revolution of the crank B is checked.

10 In Fig. 5, we illustrate a modification of the crank B showing the crank formed of three pieces, S, S^1 and S^2 . The parts S and S^2 are slotted and S^1 is fitted with shoulders to engage said slots and S^1 is threaded upon 15 the ends to engage the thumb nuts $s s$. The points $s^1 s^1$ represent the bearing faces which engage the chains x and x^1 , described hereinbefore, and by use of the slotted connection just described the swing of the points 20 $s^1 s^1$ in the revolution of the crank may be regulated to care for the different dampers to which the device may be attached.

It is our design to operate our device by means of electric circuits. To this end, we 25 provide the plugs E and E^1 , which project through the face of the chest A and are insulated therefrom. The inner ends of the said plugs are arranged in opposition to the spring tongue b^6 attached to the cross arm b^4 and in the revolution of the cross arm b^4 , the spring tongue b^6 engages alternately 30 the said plugs E and E^1 . Also passing through the face of the chest A, and insulated therefrom is the plug E^2 .

35 We design a thermostat which is connected permanently through a battery V with the plug E^2 , and therefrom with the electro magnet D. A connection is made between the magnet D and the chest A, and 40 the cross arm b^4 being in direct connection with the chest A, takes the electric contact from the said chest A. The thermostat T has connection with the plugs E and E^1 , one of which plugs is at all times, when the 45 device is at rest, in contact with the spring tongue b^6 , and through it in contact with the cross arm b^4 , and the chest A. We provide in the electric circuits a clock device N, by means of which the current can be broken.

50 One wire is connected with the clock and insulated therefrom at n to which point a stud protrudes from the clock. The other wire is connected with the alarm key n^1 , which in the winding of the alarm is turned 55 away from the stud n . When the alarm is released the key n^1 revolves until it comes into contact with the stud n which closes the circuit.

In order to operate the device without the 60 use of the thermostat T we provide a short circuit by tapping the battery wire at M and connecting it by means of a spring contact with the other wire grounded in the chest A. By the use of this short circuit, the 65 dampers may be opened or may be closed at

will, without the use of the thermostat to close the circuit.

What we claim as our invention is:—

1. In a damper regulator, the combination with a mechanism consisting of a crank 70 shaft, opposed cranks secured to said shaft, means for connecting said cranks with dampers and weight adapted to revolve said shaft, a thermostat, an electro-magnet and an armature fitted with a lug projecting from the 75 face thereof, of a stop adapted to hold said shaft against the action of said weight, said stop being fitted with an aperture larger than the said lug fitted upon the said armature, said lug being adapted to lie within 80 the aperture of said stop, whereby the said armature being attracted to said magnet, strikes a hammer blow against the apertured side of said stop thereby releasing the said shaft, substantially as described and for 85 the purposes herein set forth.

2. In a damper regulator, the combination with a thermostat, a crank shaft, opposed cranks attached thereto, means for connecting said cranks with dampers, a 90 weight adapted to revolve said shaft, a stop adapted to hold said shaft against the action of said weight, of a mechanism consisting of a hammer adapted to strike a blow upon the said stop whereby the said shaft is 95 released from the said stop, and electrical means for driving said hammer.

3. In a damper regulator, the combination with a thermostat and crank shaft, opposed cranks secured thereto, a sprocket engaging said shaft, means whereby said sprocket is allowed to turn freely in one direction and to be held rigidly against movement in the opposite direction upon said shaft, a weight bearing chain fitted 105 upon said sprocket, a stop engaging said shaft, of a hammer adapted to engage said stop by hammer blow whereby said shaft is released from said stop, electrical means whereby said hammer is actuated, means for 110 reengaging said shaft with said stop, and a dash pot adapted to control the speed of the revolution of the said shaft.

4. In a damper regulator, the combination with a thermostat, a crank shaft, opposed cranks attached thereto, means for connecting said cranks with dampers, a weight adapted to revolve said shaft, a stop adapted to hold said shaft against the action of the said weight, of means for releasing 115 the said shaft from the said stop, consisting of a hammer and electrical means for driving the said hammer against the said stop.

5. In a damper regulator, the combination with a thermostat, a crank shaft, opposed cranks attached thereto, means for connecting said cranks with dampers, a weight adapted to revolve the said shaft, a stop adapted to hold said shaft against 120 125 130

the action of the said weight, of a mechanism adapted to release the said shaft from the said stop consisting of a hammer and electrical means for driving the same against 5 said stop, and automatic means for reengaging said shaft with said stop.

6. In a damper regulator, the combination of a damper controlling motor, a stop for arresting the operation of said motor at certain 10 predetermined intervals of its motion, an electric circuit, a thermostat for making and breaking said electric circuit and a hammer for releasing said stop, said electric circuit constituting the means for driving 15 said hammer against said stop for releasing the latter, substantially as described.

7. In a damper regulator, the combination of a damper controlling motor, a retarding means therefor, a stop for arresting the 20 operation of said motor at certain predetermined intervals of its motion, an electric circuit, a thermostat for making and breaking said electric circuit and a hammer for releasing said stop, said electric circuit constituting the means for driving said hammer 25 against said stop for releasing the latter, substantially as described.

8. In a damper regulator, the combination of a damper controlling motor, a stop for 30 automatically arresting the operation of said motor at certain predetermined intervals of its motion, an electric circuit, a thermostat for making and breaking said electric circuit, a hammer for releasing said stop, said 35 electric circuit constituting means for actuating the said hammer, the said hammer being automatically restored to its striking position.

9. In a damper regulator, the combination 40 of a damper controlling motor, a stop for automatically arresting the operation of said motor at certain predetermined intervals of its motion, a hammer for releasing said stop and means for actuating said hammer, the said hammer being automatically restored to its striking position.

10. In a damper regulator, the combination 45 of a damper controlling motor, a retarding means therefor, a stop for automatically arresting the operation of said motor at certain predetermined intervals of its motion, a hammer for releasing said stop, and

means for actuating said hammer, the said hammer being automatically restored to its striking position.

55

11. In a damper regulator, the combination of a damper controlling motor, a retarding means therefor, a stop for automatically arresting the operation of said motor at certain predetermined intervals of its motion, a hammer for releasing said stop and means for actuating said hammer, the parts being so constructed and arranged that the hammer is caused to strike said stop and to be automatically restored to its striking 60 position.

12. In a damper regulator, the combination of a damper controlling motor, a retarding means therefor, a stop for automatically arresting the operation of said 65 motor at certain predetermined intervals of its motion, a hammer for releasing said stop and thermostat controlled means for actuating said hammer, the parts being so constructed and arranged that the hammer is caused to strike said stop and to be automatically restored to its striking position.

13. In a damper regulator, the combination of a damper controlling motor, a stop for automatically arresting the operation of 70 said motor at certain predetermined intervals of its motion, a hammer for releasing said stop and means for actuating said hammer, the parts being so constructed and arranged that the hammer is caused to strike 75 said stop and to be automatically restored to its striking position.

14. In a damper regulator, the combination of a damper controlling motor, a stop for automatically arresting the operation of 80 said motor at certain predetermined intervals of its motion, a hammer for releasing said stop and thermostat controlled means for actuating said hammer, the parts being 85 so constructed and arranged that the hammer is caused to strike said stop and to be automatically restored to its striking position.

15. In a damper regulator, the combination of a damper controlling motor, a stop for automatically arresting the operation of 90 said motor at certain predetermined intervals of its motion, a hammer for releasing said stop and thermostat controlled means for actuating said hammer, the parts being 95 so constructed and arranged that the hammer is caused to strike said stop and to be automatically restored to its striking position.
